UNITED STATES PATENT OFFICE.

ERNEST LENNOX DUNAND, OF LONDON, ENGLAND.

LAMP SHADE.

Application filed December 8, 1926, Serial No. 153,241, and in Great Britain July 21, 1926.

The invention relates to lamp shades primarily for electric incandescent lamps.

The shade is adapted to contain and support the lamp, the shade and its lamp being a freely movable unit either at the end of flexible electric leads, or on a suitable pedestal. The invention is, however, particularly intended for use without a pedestal, being furnished instead with clips, or other suitable suspension securing means, whereby it may be instantly and easily attached to or detached from a convenient fixture such as a horizontal bed rail, a rack surmounting an office desk, and so on. In this latter respect an important object of the invention is to construct a lightweight shade carrying the lamp which can be attached to a bed rail immediately above the occupant's eyes, direct rays being shaded, and which is capable of being produced in artistic manner.

Broadly, according to the invention, the lamp shade is of box-like form constructed of translucent or semi-transparent material to transmit diffused light all around and contains a support for a lamp, the shade entirely surrounding the lamp except at its base which has an opening and a screened part, the latter being so disposed with relation to the lamp as to intercept and diffuse direct downward rays, there being incorporated means to support the shade. In one form, the shade consists of a hollow structure of semi-transparent material (such as silk or other fabric, paper or the like, stretched or mounted on a wire frame) which has a forward part in the form of a closed-in hood totally concealing the lamp, which hood is an extension of a rear part open at the bottom to allow access to the lamp, a lamp mounting or holder of any description being built in with or mounted in the hood.

The said invention will be better understood by reference to the following description of an embodiment in greater detail, by way of example, which is illustrated in the accompanying drawings, wherein:

Figure 1 is a front elevation.

Figure 2 is a side view.

Figure 3 is an inverted plan and

Figure 4 is an underneath perspective view.

The shade, in this embodiment, is composed of silk or other material stretched

over a stiff wire foundation frame or cage—more particularly indicated in Figure 4. The shade may be artistically ornamented by printing, painting, embroidering or otherwise. The rear part 2 of the shade is substantially semi-circular in vertical position, i. e. the wire can be a pair of spaced apart semi-circles 4 joined by suitable cross-wires, and towards the front the aforesaid hood 3 projects visor-like in the approximate form of quarter of a sphere. In an underneath view—see Figure 3 particularly—the bottom of the rear part 2 between the two semi-circular wires is rectangular, and the bottom of the hooded front 3 is semi-circular—this being merely a general description.

The foundation of the said hood may be a number of downwardly curved wire ribs 5 extending from the two erect semi-circles 4 of the rear.

In covering the frame to form the shade, the rectangular bottom of the rear part 2 is left open, whilst the semi-circular bottom of the hood 3 is covered in with the rest of the shade.

A wire loop 6 is formed in or attached to one of the ribs 5 of the hood 3, and projects interiorly of the shade to support an electric lamp which is housed well inside the hood 3 above the covered bottom thereof. Or, of course, any other lamp mounting may be used. The electric wires are led in through any suitable orifice in the shade or through the opening in the bottom. This refers to the leads of an electric incandescent lamp, and the flex of a separate suspended switch if used. It is considered unnecessary to show any opening or openings, as they may be disposed anywhere convenient.

The wires forming the foundation or cage as above described may be bent into a hook or hooks at the back of the rear part to support the lamp and shade on the top rail of a bed for instance. Or other securing means may be used. Weighted ribbons 1 are shown by way of example which are secured to the back of the shade, and adapted to hang over the head of the bed to support, by counterbalancing, the shade.

I am aware that in lighting means for picture auditoriums, an opaque reflecting box with an underneath opaque portion screening direct rays from an enclosed lamp

has been formed with means to mount same detachably to a wall or ceiling bracket, but I do not claim this.

I claim:

- 5 A lamp shade of box-like form comprising a wire framework having a rear portion consisting of two spaced-apart erect semi-circular ribs joined by cross wires, and a front portion of substantially quarter-
10 spherical form consisting of curved wire ribs extending from one of said erect semi-circular ribs, a cover of light diffusing material on said frame which completely covers same except at the bottom for a rectan-

gular space between the bases of the erect 15 semi-circular ribs, and which cover closes the bottom of the quarter-spherical front portion, a lamp holder within the frame adapted to hold the lamp so that the same assumes a position in the quarter-spherical 20 front portion, and flexible counter-weight elements attached to one of the erect semi-circular ribs for supporting the shade on a rail or the like.

In testimony whereof, I have signed my 25 name to this specification at London, England, this 11th day of November, 1926.

ERNEST LENNOX DUNAND.
